US0D1078643S

(12) **United States Design Patent** (10) **Patent No.:** **US D1,078,643 S**
(45) **Date of Patent:** **** Jun. 10, 2025**

(54) **ELECTRICAL CONNECTOR**

(71) Applicant: **SMK Corporation**, Tokyo (JP)
(72) Inventor: **Tomohito Okamura**, Tokyo (JP)
(73) Assignee: **SMK Corporation**, Tokyo (JP)

(**) Term: **15 Years**

(21) Appl. No.: **29/872,477**

(22) Filed: **Mar. 14, 2023**

(30) **Foreign Application Priority Data**

Sep. 16, 2022 (JP) ..... 2022-019965 D
Feb. 6, 2023 (JP) ..... 2023-002010 D

(57) **CLAIM**

The ornamental design for an electrical connector, as shown and described.

DESCRIPTION

FIG. 1 is a front, bottom, left side perspective view of an electrical connector of first embodiment, showing my new design;

FIG. 2 is a rear, bottom perspective view thereof;

FIG. 3 is a front elevation view thereof;

FIG. 4 is a rear elevation view thereof;

FIG. 5 is a top plan view thereof;

FIG. 6 is bottom plan view thereof;

FIG. 7 is a right side view thereof; and

FIG. 8 is a left side view thereof.

FIG. 9 is a front, bottom, left perspective view of an electrical connector of second embodiment, showing my new design;

FIG. 10 is a rear, bottom perspective view thereof;

FIG. 11 is a front elevation view thereof;

FIG. 12 is a rear elevation view thereof;

FIG. 13 is a top plan view thereof;

FIG. 14 is a bottom plan view thereof;

FIG. 15 is a right side view thereof; and,

FIG. 16 is a left side view thereof.

The broken lines depict portions of the electrical connector that form no part of the claimed design.

1 Claim, 16 Drawing Sheets
